ber 13 has a top wall 13c which is truly sector-shape in plan save for the slight curvatures at the corners. Extending downwardly from this top wall is a peripheral flange whose side walls 13a are curved inwardly intermediate their ends convex inwardly in the direction of their length as shown in dotted lines in Fig. 5 and shown in dot-dash lines in Fig. 6. An arcuate end flange 13b connects the two side flanges 13a.

The use of the device shown in Figs. 4, 5 and 6 should now be apparent. In this form of my device, the flange of the cover 13 fits outside of the walls of the box. The cover may be placed upon the box either by placing the end wall or flange 13b of the cover against the end wall 12b of the box and then bringing the apex 13d down toward the apex 12d. Conversely, the apex 13d may be placed upon the apex 12d and the box cover then pushed down until the end wall 12b of the box is covered by the end flange 13b of the cover. In either case, the side walls 12a of the box cam the curved walls or flanges 13a of the cover from the dot-dash position of Fig. 6 to the full line position shown there, whereupon the side walls of the cover are held firmly on the box. The material of that form of my device shown in Figs. 4, 5 and 6 is of a generally rigid but flexible material such as one of the well known synthetic resins on the market which will take a permanent set in the positions shown at 13a in Fig. 6 but which will easily be cammed outwardly to the position shown in full lines at 13a in Fig. 6 after which the cover will grip the sides of the box tightly because of the permanent set of the material of which the cover is made.

What I claim is:

A container having box and top members, said box member having a sector shape bottom and

upstanding side walls including two radially extending walls and an arcuate wall, said top member having sector shape top and downturned side walls including two radially extending walls and an arcuate wall, the side walls of one of said members fitting telescopingly outside the side walls of the other of said members, said first named member having its radially extending walls of stiff resilient material having a permanent set with an intermediate portion of each of its radially extending walls bent convex inwardly in the direction of its length out of line with and in a direction to press against the associated telescoping radially extending walls of the other member and cammed into line therewith when said top member is placed on said box member, said radially extending walls of said one member extending in a smooth curve convex inwardly and said radially extending walls of the other member being substantially rectilinear.
